UNITED STATES PATENT OFFICE.

BENJAMIN KNOPP, OF BLOOMVILLE, OHIO.

POST-HOLE AUGER.

SPECIFICATION forming part of Letters Patent No. 232,041, dated September 7, 1880.

Application filed June 18, 1880. (No model.)

To all whom may it concern:

Be it known that I, BENJAMIN KNOPP, a citizen of the United States, residing at Bloomville, in the county of Seneca and State of Ohio, have invented new and useful Improvements in Post-Hole Augers, of which the following is a specification.

The invention relates, principally, to that class of post-hole borers in which oppositely-bladed wings are driven by a centering handle or pole attached thereto; and the object of my improvements is to provide means for firmly bracing the handle to the wings and for securely seating the adjustable cutting-bits, and while so doing to preserve the utmost simplicity of construction. The construction used to carry out these objects will be hereinafter fully described, and the improvements pointed out in the claims.

20 In the accompanying drawings, Figure 1 represents a perspective of a post-hole auger embracing my invention; Fig. 2, a top view; Fig. 3, a section on the line *x x* of Fig. 2; Fig. 4, a section on line *y y* of that figure; Fig. 5, a detail of one of the plates which carry the bits; and Fig. 6, a sectional detail, showing the manner of fastening the hand cross piece or bar to the centering-handle.

30 The two plates *A A*, which carry the bits or cutters *B B*, are cast with top raised ledges, *a a a a* and *b b*, the former producing a bracing recess for the reception of the connecting-bar *C*, and acting also as stop-shoulders for the bits *B* to bear against, while the latter act merely as shoulders for said bits.

35 By reason of the connecting-bar *C* resting in the bearing-recess formed by the raised ledges *a*, one screw *c* is only required to fasten each one of the plates *A* to the bar *C*, and thus to the centering-handle *D*, as will be presently described, and this connecting-bar is not only securely held, but thoroughly and securely braced against the severe lateral pressure. No strain whatever is upon the fastening-screws *c c* except in lifting out the dirt; but in the act of boring the strain is all distributed against the shouldered ledges *a*, as above described. This connecting-bar *C* has a raised curved portion, *M*, bridging the transverse space between the plates *A A*, and within which the bits work, and is provided with a screw-threaded open-

ing, into and through which the centering-rod is screwed to fasten it. This bridge *M* is sufficiently high to permit the passage of dirt.

The oppositely-placed cutters or bits *B B* rest upon and are fastened by single screws *f* to downwardly-inclined seats *g g* of said plates, and are securely shouldered against the before-described ledges *a b*, and as these ledges *a b* form an intervening shallow valley, *k*, the tops of the cutters are beveled at *l l*, to form a flush continuation and permit the free flow of the dirt into said valley.

45 It will be observed that only four screws or rivets are required in all the fastening of the boring parts.

The cutting-bits are removable, and may be interchanged or reversed when desired.

50 It is well understood that during the progress of boring the auger is raised and the dirt dumped from time to time, more frequently in wet ground than in dry.

The cross-bar *K* of the centering-handle is prevented from turning, or, rather, caused to turn with said handle, by reason of a square shoulder, *m*, on the centering-handle, over which the square socket *o* of a casting, *n*, fits, and through which casting the said centering-handle passes. This casting has a concave seat for the cross-bar of the handle, and the device is secured by a nut, *p*, and concave washer *r*, as shown. By this device the cross-bar is not only prevented from splitting, but is firmly held as a fixture of the handle.

55 The centering-point *x* extends below the plates to maintain the centering of the auger.

I claim—

1. In a post-hole auger, the plates *A A*, provided with the ledges *a a a a*, forming a bearing-recess, in combination with the connecting-bar *C*, secured in said recess, and the centering-handle, substantially as described.

2. In a post-hole auger in which are combined, as described, the plates *A A*, provided with the ledges *a a a a*, forming a bearing-recess, a centering-handle and a connecting-bar, *C*, the said connecting-bar *C* having the curved bridge *M*, substantially as and for the purpose set forth.

3. In a post-hole auger, the plates *A A*, provided with downwardly-inclined seats *g* and shoulders formed by raised ledges *a b* for the

bits B, secured by single screws and having a bearing against said shoulders, substantially as set forth.

4. In a post-hole auger, the valleys *k* in the 5 plates A, between the raised ledges *a b*, in combination with the inclined seats *g* and the bits B, beveled at *l*, substantially as and for the purpose set forth.

In testimony whereof I have hereunto set my hand in the presence of two subscribing to witnesses.

BENJAMIN KNOOPP.
